(57) **CLAIM**

The ornamental design for an aircraft interior, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of the aircraft interior;

FIG. 2 is another perspective view thereof;

FIG. 3 is a rear perspective view thereof;

FIG. 4 is a side view thereof;

FIG. 5 is another side view thereof;

FIG. 6 is a further side view thereof;

FIG. 7 is a side rear perspective view thereof; and,

FIG. 8 is a side front perspective view thereof.

The grayed-out areas surrounded by broken lines in the drawings depict portions of the aircraft interior that form no part of the claimed design.

The claimed design covers the composite of the portions of the aircraft interior depicted in FIGS. 1-8; any portion(s) of the aircraft interior not depicted in FIGS. 1-8 form no part of the claimed design.
